E. A. FREDRICKSON

ATTACHMENT FOR REVOLVERS

Filed Oct. 30, 1922

FIG. 1.

FIG. 2.

FIG. 3.

FIG. 5.

Inventor

Erick A. Fredrickson

By *William J. Jacobs*

Attorney

UNITED STATES PATENT OFFICE.

ERICK A. FREDRICKSON, OF DRAYTON, NORTH DAKOTA.

ATTACHMENT FOR REVOLVERS.

Application filed October 30, 1922. Serial No. 597,891.

To all whom it may concern:

Be it known that I, ERICK A. FREDRICKSON, a citizen of the United States, residing at Drayton, in the county of Pembina and State 5 of North Dakota, have invented certain new and useful Improvements in Attachments for Revolvers, of which the following is a specification.

This invention relates to flashlight attachments for fire arms and its principal object 10 is to provide a flash light or illuminating attachment for fire arms which can be conveniently operated to illuminate the object or target to be shot at.

15 A further object of the invention is to provide an illuminating attachment for revolvers and other fire arms and includes a circuit closer operable from a point adjacent the usual firing trigger thus enabling 20 both the circuit closer and firing trigger to be actuated by the same finger.

It is also an object of the present invention to provide an illuminating attachment for fire arms which can be conveniently applied 25 to any type of fire arm and is such as to permit the fire arm to be operated without any interference whatsoever.

With the preceding and other objects and advantages in mind, my invention consists 30 in the novel combination of elements, constructions and arrangement of parts in operation to be hereinafter specifically referred to, claimed and illustrated in the accompanying drawing, wherein—

35 Figure 1 is a side elevation of my invention associated with a revolver.

Figure 2 is a front end elevation of the same.

Figure 3 is a side elevation of the circuit 40 closing element.

Figure 4 is a side elevation of the circuit closing actuating trigger, and

Figure 5 is an elevation of the attaching 45 plate used in the invention.

Referring in detail to the drawing wherein like characters of reference denote like parts throughout the several views, the numeral 5 designates a conventional fire arm which in this instance is illustrated as a revolver.

50 In this connection I wish to emphasize the fact that the invention is also applicable to rifles, shot guns and other weapons of this general character.

55 My invention as reduced to practice comprises a pair of straps or clamps 6 which include circular parts 7 which embrace a

portable flash light indicated at 8 and extending longitudinally beneath the barrel of the revolver, and jaws 9 which embrace the revolver barrel and are retained in clamped position thereon by bolts 10. As illustrated in Fig. 2 the flash light includes a laterally disposed reciprocable switch or contact 11 arranged adjacent the forward end thereof.

A plate 12 is attached to one side of the revolver 5 in proximity to the firing trigger thereof and pivoted to this plate 12 is an actuating circuit closing trigger 13 having an extension 14 to which a contractile coil spring 15 is attached, the latter having one 65 end attached to a lug 16 formed on the rear end of the plate 12. Slidably mounted longitudinally along the flash light 8 and passing through a guide 17 formed on one side of one of the clamps 7 is a reciprocal circuit closing 70 bar 18 which is engaged with the contact or circuit closer 11 in any preferred manner so that when actuated the flash light circuit will be opened or closed. A link 19 is pivotally connected with the rear end of the circuit 75 closing bar 18 and is provided with a shoulder 20 to limit the pivotal movement of this link in a downward direction, the opposite end of the link being pivotally connected with the extension 14 as indicated 80 at 21.

In the operation of the device it will be seen that upon pulling the trigger 13 backward the bar 18 will be shifted longitudinally forwardly to actuate the circuit closer 90 11. Reversely upon release of the trigger 13 will return the parts to normal position and ready for the next operation. With my improved illuminating attachment for fire arms it can be readily seen 95 that when it is necessary to use the fire arm in the dark, it is only necessary to manipulate the trigger 13 and the target or object will be illuminated. Moreover, the device will be quite advantageous as soon as the 100 trigger is released the circuit will be broken to the lamp bulb and thereby preventing an opponent from getting in range of the person carrying the revolver.

From the foregoing it will be seen that I have provided a simple, inexpensive and efficient means for carrying out the objects of the invention, and while I have particularly described the means best adapted to perform the functions set forth, various 105 changes in form, proportion and in the minor details of construction may be re-

sorted to without departing from the spirit or sacrificing any of the principles of the invention.

What I claim as new and desire to secure by Letters Patent is:—

In a device of the class described the combination with a fire arm including a barrel; of a flash light removably secured to and suspended below said barrel, said flash light being provided with a circuit closing operating member and means for manually actuating said member comprising a plate secured to the body of said fire arm, said plate being provided with a depending central portion and a rearwardly projecting lug, a trigger

fulcrumed intermediate of its ends on the depending central portion of said plate, a longitudinally slideable bar supported immediately adjacent said flash light having connection with said circuit closing operating member, a link pivotally connecting the inner end of said bar with the inner end of said trigger, and a coil spring having one end engaged with said trigger intermediate its fulcrumed and inner end and having its opposite end engaged with the rearwardly projecting lug on said plate. 20 25

In testimony whereof I affix my signature.

ERICK A. FREDRICKSON.
